MOTION PICTURE MACHINE

Application filed September 14, 1929. Serial No. 392,623.

My invention relates to means for synchronizing the operation of a motion picture projecting machine and a sound reproducing machine.

5 An important object of the invention is to provide adjustable driving connecting means between one of the rotating parts of a motion picture projecting machine and the rotatable platen of the sound reproducing machine, whereby the synchronism of the operation of the two machines may be readily restored and maintained.

10 A further object of the invention is to provide means of the above mentioned character which is adjustable to drive the platen in opposite directions, so that records feeding both inwardly and outwardly may be employed.

15 A further object of the invention is to provide means whereby the platen may be supported and rotated in a level position, when it is desired to tilt that portion of the motion picture projecting machine to which the sound reproducing machine is attached.

20 A further object of the invention is to provide means whereby the driving connecting means may be quickly adjusted and to also provide for a fine adjustment.

25 A further object of the invention is to provide means whereby a portion of the driving connecting means is removable as a unit.

30 A further object of the invention is to provide means whereby the sound producing machine may be supported at a convenient elevation, for proper manipulation by the operator.

35 A further object of the invention is to provide means of the above mentioned character which is simple in construction, strong, durable and reliable in operation.

40 Other objects and advantages of the invention will be apparent during the course of the following description.

45 In the accompanying drawings, forming a part of this specification, and in which like numerals are employed to designate like parts throughout the same,

Figure 1 is a front elevation of apparatus embodying my invention,

50 Figure 2 is a side elevation of the driving shaft and coupling, parts in section,

Figure 2^a is a side elevation of a removable unit of the driving connecting means,

Figure 3 is a plan view of the sound reproducing machine, and,

Figure 4 is a side elevation of the same, 55 showing the angular adjustability of the platen support.

Figure 5 is a sectional view taken on line 5—5 of Fig. 1.

In the drawings, wherein for the purpose 60 of illustration, is shown a preferred embodiment of my invention, the numeral 10 designates a motion picture projecting machine of any well known or preferred type, embodying a lens 11 and support 12. The parts 10 and 12 constitute the head of the projector, and are supported for angular adjustment. As is well known, the ordinary type of motion picture projecting machine is driven by 65 a motor and the film is advanced by the driving action of the motor upon a chain of gears. One of these rotatable gears is designated by the numeral 13 and is shown as equipped with a hub 14, rotatable therewith. The rotating 70 element or gear 13 of the motion picture projecting machine is also employed to drive the sound reproducing machine, in my present invention, in a manner to properly synchronize the operation of the two machines. 75

In accordance with the present invention, the sound reproducing machine is attached to the motion picture projecting machine adjacent to the head of the same, with the advantage that the sound reproducing machine is supported at a convenient elevation and is also free from the injurious effect of vibrations which usually occur in connection with machines wherein the sound reproducing unit is not directly supported from the head of the motion picture machine. In accordance with the present invention, I provide a generally rectangular supporting frame 15, including horizontal bars 16 and 17 and a vertical bar 18. The bar 16 is rigidly attached to the head 10 by the projector, while the bar 17 may be rigidly attached to the base 12 adjacent to the head 10. 85

Arranged above the bar 16 and bolted or otherwise rigidly secured thereto is a pair 90 of ears 19, which are apertured to receive 95

bolts or pivots 20 passing through the apertured ears 21 of an inverted U-shaped support 22. This support may be turned upon the pivots 20 for effecting relative angular adjustments between the support 22 and the frame 15. The ears 19 have screw-threaded openings formed therein for receiving the screw-threaded ends of clamping screws 23, operating through segmental slots 24, Figure 4, also formed in the ears 19. By manipulation of the clamping screws, the support 22 may be locked in adjustment upon the ears, at selected angular positions with relation thereto.

15 The numeral 24' designates a rotatable platen or table having a hub 25 arranged beneath the same and rigidly secured thereto. This hub and platen have an upwardly tapering opening to receive a tapered pin 26, carried by a rotating shaft section 27. This shaft section is formed integral with the pin 26. The pin 26 being tapered is locked to the hub and platen for rotation therewith, when these parts are suitably driven together. The shaft section 27 is journaled through a suitable bearing 28 in the top of the support 22, and a ball bearing 29 is preferably arranged between the hub 25 and the bearing 28. One element 30 of a universal joint is permanently and rigidly mounted upon the shaft 27 and is preferably detachably connected with the companion element 31 of the universal joint. This companion element is rigidly and permanently mounted 35 upon a vertical drive shaft 32. The drive shaft 32 is preferably vertically arranged, and disposed upon one side of the same, in parallel relation thereto, is a feed screw 33. The vertical drive shaft 32 and feed screw 33, have their upper ends journaled in bearings 34 and 35, respectively, carried by a common bed plate 36, detachably secured to the upper bar 16 by bolts 37, or the like. The upper bar 16 is provided with a transverse slot 38, to receive the shaft 32. The lower ends of the drive shaft 32 and feed screw 33 are journaled in bearings 39 and 40, carried by a common bed plate 41, detachably secured to the lower bar 17 by bolts 42 or the like. The bar 17 has a transverse slot 43, for the passage of the lower end of the feed screw, as shown. It is thus seen that by disconnecting the elements 30 and 31 of the universal joint, that the bed plates 36 and 41 may be separated from the bars 16 and 17, and the drive shaft 32 and feed screw 33, and elements carried thereby, removed as a unit.

Arranged within the frame 15 is a horizontal connecting shaft 44, the outer end of which is journaled in a bearing 45, carried by a vertical bar 46, attached to the bars 16 and 17. The inner end of the shaft has a sleeve 46 splined thereon, to move longitudinally of the same and turn therewith. This sleeve carries a socket 47, formed integral

with the same, and this socket is adapted to engage over the hub 14 of the gear or rotating element 13 and to be clamped thereto by means of a bolt 48 or the like. Arranged within the sleeve 46 is a suitably stiff compressible coil spring 49, engaging between the hub 14 and the connecting shaft 44 and tending to shift the connecting shaft longitudinally outwardly.

Rigidly mounted upon the outer end of the connecting shaft 44 is a vertically disposed friction disc 50 formed of metal or like material, and the vertical drive shaft 32 is disposed diametrically with respect to this vertical disc. A friction wheel 51 is arranged to engage with the face of the disc 50 and is splined upon the vertical drive shaft 32, to move longitudinally thereof and turn therewith. The periphery of the friction wheel 51 is preferably formed of leather, fabric or other suitable material. The friction wheel embodies a hub 52, having a groove 53, to receive a shifting fork 54, secured to a sliding element or block 55. This sliding element or block has a screw-threaded opening to receive the feed screw 33. The spring 49 forces the disc 50 into proper frictional engagement with the wheel 51, whereby these elements rotate without slippage.

A quick adjustment of the friction wheel 51 is effected by means of a large gear 55, supported upon a shaft 56, attached to the vertical bar 18. This large gear engages a smaller gear 57, rigidly mounted upon the lower end of the feed screw 33. A knurled wheel 58 is rigidly mounted upon the feed screw 33 beneath the smaller gear 57 and is employed in effecting fine adjustments of the friction wheel 51.

The slide 55 is provided with a pointer 59, for co-action with a scale 60. This scale is preferably graduated in tenths of an inch, or finer, if desirable, and runs from zero at the center outwardly in opposite directions.

Rigidly attached to the support 22, above its pivots 20, are a pair of arms 61, extending parallel with the platen 24 and radially beyond the same. These arms carry at their outer ends a platform 62, rigidly secured thereto and an arm 63 is supported upon the platform, to swing vertically and horizontally, and for this purpose has a universal mounting upon a support 64. This arm is equipped at its free end with a reproducer 65, such as the modern type of electrical reproducer or pick-up, having a needle to engage in the grooves of the record to be placed upon the platen 24. As the construction of the sound reproducing means, per se, is old, no further description of the same is thought to be necessary. It should be stated, however, that in connection with records to be played with motion picture projecting machines, there are two types of records. One type is such that the needle travels inwardly, and

the other outwardly, when the record is played. By the means which I have provided, the direction of rotation of the platen may be readily reversed, making it possible to use 5 the apparatus with either of these two types of records.

In the operation of sound reproducing machines, employing a record, it has been found very difficult to synchronize the reproduction 10 of the sound with the projection of the picture, and more difficult to restore the synchronism when it is broken. This is due largely to the fact that it has been the practice to use a driving connection between the motion picture projecting machine and the sound reproducing machine, which is of such a character that considerable lost motion occurs. Further, these driving connections are such that they are not adjustable to restore the loss of 15 synchronism. The ordinary practice is to attempt to restore the synchronism by lifting the needle from the groove of the record and returning the same to another point of the groove.

20 In the use of my invention, the rotation of the gear 13 is imparted to the shaft 44, driving the disc 50, which in turn drives the friction wheel 51. This rotation is imparted to the shaft section 27 through the medium of 25 the universal joint. The shaft section 27 rotates the platen 24, carrying the record. The friction wheel 51 is adjusted radially upon the disc 50 by turning the feed screw 33, so that the projection of the picture and the reproduction of the sound is synchronized. Should the synchronism be broken during the 30 operation, it is restored by the radial adjustment by the friction wheel 51. The extent of radial adjustment of the friction wheel 51 is indicated by the pointer 59 upon the scale 60. When the pointer 59 is at zero upon the scale 35 the wheel 51 is at the center of the friction disc 50. By shifting the friction wheel 50 upon the opposite side of the center of the friction disc 50, the direction of rotation of the platen 24 may be reversed. It is thus seen that not only the direction of rotation of the disc may be reversed, but its speed of rotation when turning in either direction may be accurately varied for effecting proper synchronization.

Another cause of the imperfect reproduction of sound by machines of this general type is that the platen carrying the record 40 become inclined when it is necessary to change the inclination of the head of the projector. When rotating the record at an inclination, the needle is caused to scrape upon the side wall of the groove, distorting the sound and 45 frequently producing a rasping noise. This difficulty is entirely overcome in the use of my machine, as the platen is maintained level irrespective of the angularly adjusted position of the head of the projector. The level of 50 the platen 24 is indicated by a spirit level 62',

which may be conveniently mounted upon the side of the platform 62, as shown.

It is to be understood that the form of my invention, herewith shown and described, is to be taken as a preferred example of the 70 same, and that various changes in the shape, size and arrangement of parts, may be resorted to without departing from the spirit of my invention, or the scope of the subjoined claims.

Having thus described my invention, I claim:—

1. The combination with a motion picture projecting machine embodying a head angularly adjustable in a generally vertical plane, of a support mounted upon the head, a sound reproducing machine embodying a rotatable platen, means for supporting the platen and mounted upon the support, said means being angularly adjustable in a generally vertical plane so that the platen may be maintained level when the head is at an inclination, and means to drive the platen from a rotating element of the projecting machine.

2. The combination with a motion picture projecting machine embodying a head angularly adjustable in a generally vertical plane, of a supporting element mounted upon the head, a sound reproducing machine embodying a rotatable platen, supporting means for the platen mounted upon the supporting element, said supporting means being angularly adjustable in a generally vertical plane so that the platen may be maintained level when the head is inclined, a shaft section connected with the platen to drive the same, a drive shaft mounted upon the supporting element, a universal joint connecting the shaft section and drive shaft, and positive driving means 105 operated by a rotating element of the projecting machine and serving to rotate the drive shaft.

3. The combination with a motion picture projecting machine embodying an angularly adjustable head, of a supporting element mounted upon the head, a sound reproducing machine embodying a rotatable platen, supporting means for the platen angularly adjustably mounted upon the supporting element so that the platen may be maintained level when the head is inclined, a vertical shaft section connected with the platen to drive the same, a normally vertical drive shaft mounted upon the supporting element, a universal joint connecting the shaft section and drive shaft, a horizontal connecting shaft mounted upon the supporting element and connected with a rotating part of the projecting machine, a friction disc carried by the 120 connecting shaft, a friction wheel splined upon the drive shaft and engaging the friction disc, and means to shift the friction wheel longitudinally upon the drive shaft.

4. The combination with a motion picture

- projecting machine including a head which is angularly adjustably supported, of a supporting element directly mounted upon the head, a sound reproducing machine including
- 5 a rotating platen, a support for the platen pivotally mounted upon the supporting element so that the platen may be maintained level when the head is inclined, means to clamp the support in the selected adjusted position,
- 10 a vertical shaft section connected with the platen, a normally vertical drive shaft mounted upon the supporting element, a universal joint connecting the drive shaft with the shaft section, a feed screw extending longitudinally of the drive shaft and mounted upon the supporting element, a friction wheel splined upon the drive shaft, a shifting device for the friction wheel carried by the feed screw, means to turn the feed screw, a friction disc engaging the friction wheel, and a horizontal connecting shaft secured to the friction disc and a movable part of the projecting machine.
- 15 5. The combination with a motion picture projecting machine embodying an angularly adjustably supported head, of a supporting frame directly mounted upon the head, a sound reproducing machine embodying a rotating platen, means to support the platen
- 20 and angularly adjustably mounted upon the frame, a shaft section to drive the platen, a drive shaft, a detachable universal joint connecting the drive shaft and shaft section, a feed screw extending longitudinally of the
- 25 drive shaft, a friction wheel splined upon the drive shaft, a shifting element for the friction wheel carried by the feed screw, means to turn the feed screw, bearing means for the drive shaft and feed screw and detachably
- 30 mounted upon the frame so that the drive shaft and feed screw may be removed therefrom as a unit, a connecting shaft secured to a rotating part of the projecting machine, and a friction disc connected with the drive
- 35 shaft and engaging the friction wheel.

- 40 6. The combination with a motion picture projecting machine embodying a head angularly adjustable in a generally vertical plane, of a support mounted upon the head, a sound
- 45 reproducing machine embodying a rotatable platen, supporting means arranged between the platen and support for mounting the platen upon the support, said supporting means being adjustable in a manner to maintain the platen level when the head is at an inclination, and means to drive the platen from a rotating element of the projecting machine.

In testimony whereof I affix my signature.
GEORGE F. D. ROLLINGS.
